(57) CLAIM

The ornamental design for a garment, as shown and described.

DESCRIPTION

FIG. 1 is a front perspective view of a garment showing my new design;

FIG. 2 is a side view thereof;

FIG. 3 is a front view thereof;

FIG. 4 is a side view thereof;

FIG. 5 is a rear side view thereof; and,

FIG. 6 is a magnified view showing the claimed area.

The long and short broken lines are unclaimed boundaries of the claimed design. It is understood that the claimed design extends to these boundaries but does not include the boundaries.

The even-length broken lines shown in the drawings are directed to environment and form no part of the claimed design.
